Fig. 3

FIGURE 1 is a front view of my design for a space condition responsive instrument;

FIGURE 2 is a side view of my design looking from the left of FIGURE 1; and

FIGURE 3 is a plan view of my design looking down on FIGURE 1.

The essential features of my disclosed design reside in the portion shown in full lines in the drawing.

The undisclosed sides of the space condition responsive instrument are substantially the same in appearance as the sides shown in FIGURES 2 and 3.

The rear of the instrument is a mirror image of the front except that the center section is plain and unornamented.

I claim:

The ornamental design for a space condition responsive instrument, substantially as shown and described.
